UNITED STATES PATENT OFFICE

FRANK T. LIPPINCOTT, OF NEWARK, OHIO.

HINGE.

1,009,251.

Specification of Letters Patent. Patented Nov. 21, 1911.

Original application filed October 22, 1909, Serial No. 524,073. Divided and this application filed August 5, 1910. Serial No. 575,624.

To all whom it may concern:

Be it known that I, FRANK T. LIPPINCOTT, residing at Newark, in the county of Licking and State of Ohio, have invented certain new and useful Improvements in Hinges, of which the following is a specification.

My invention is an improved hinge particularly designed for use in window construction having hinged sash carrying sections, although the invention is capable of use in other relations, and the application is a divisional part of my original application filed Oct. 22/09 Serial No. 524,073.

Generically the hinge comprises two members pivoted together and having wing plates continuously in contact with one another to limit the movement on the hinge pin, as well as to brace the joint.

More specifically the invention also resides in those novel details of construction, combination and arrangement of parts, all of which will be first fully described, then be specifically pointed out in the appended claims, and illustrated in the accompanying drawings, in which:—

Figure 1, is a central vertical cross section of a window embodying my invention. Fig. 2, is an enlarged detail perspective view of one corner of the same, showing the hinge connection between the swinging section of the window and the frame casing.

In the accompanying drawing I have disclosed my invention as applied to a window for which it is particularly adapted, the window casing 1 having the fixed grooved frame sections 2 whose grooves 2^a—2^b receive the sashes 15 and 16 respectively; the swinging frame sections 4 having the window grooves 4^a—4^b and having their upper ends 4^c normally contacting the ends 2^c of the sections 2.

In order to hold the sections 4 and 2 in proper alinement to make a continuous uninterrupted groove 2^a—4^a, or 2^b—4^b, as the case may be, from the top to the bottom of the window, when the parts are in their normal position, I have provided a special hinge composed of a plate 5 secured in the countersunk portion 4^d of the frame sections 4, which plate enters the cut-away portions 2^d of the sides 2 when the sash is in its normal position and a latch 3 has its head to engage the plate 5 and lock the sections 2 and 4 together with the sections 2 and 4 in alinement.

The lower edges of the sections 4 are square cut to leave a space between said lower edges and the sill 17, as shown by dotted lines 18 in Fig. 1, to prevent water and moisture rotting said lower edges.

The casing 1, where it joins the sill is countersunk to receive the hinge plate 6^a and it is further countersunk at 1^a to permit movement of the clip 7^a of the hinge plate 7^a hereinafter again referred to. The hinge plate 6^a is of circular arc form having a vertical edge 6^a and a front portion 6^b held in a plane at right angles to the plate 6^a, the portion 6^b having curled hinge ears 6^c, through which and through similar ears 7^c of the front plate 7^a of the hinge section 7, the hinge pin 8 passes. The hinge section 6 has its plate 6^a secured in the countersunk portion of the casing 1 by screws that pass through apertures 6^f in the plate. The plate 6^a at its upper end has a stop 6^g and near its lower end has a second stop 6^h to limit the movement of the hinge section 7 by having its clip 7^a engage said stops at the limit of movement of the hinge section in either direction.

The hinge section 7 comprises the side plate 7^a which is secured to the sides of the window sash by screws 7^f that pass through the plate 7^a, as shown in Fig. 2, the plate 7^c abutting the plate 6^a of the other hinge section 6 and having a part cut away and bent away to form a clip 7^a to securely hold the sections 6^a—7^a in contact. The hinge section 7 also includes a front plate 7^b that is secured in a countersunk portion of the window sash at the front and held in place by screws 7^e, as shown in Fig. 2, of the drawings. Thus it will be seen a very rigid hinge connection is provided for the windows between the window and frame to prevent lateral movement or separation of the window and by projecting the plates 7^a—6^a in contact with one another and holding them in contact by the clip 7^a the strain is largely removed from the hinge connection 6^c—7^c—8.

From the foregoing description taken in connection with the accompanying drawings it is thought the complete construction, operation and advantages of my invention will be readily understood by those skilled in the art to which the invention appertains.

What I claim is:

1. A fixed and a movable body, means for

hinging said movable body to said fixed body, said means comprising a pair of hinge members, one of said hinge members consisting of a main arc plate 6^a, having its edge 6^a curved in the arc of a circle, said plate 6^a at its upper end having a stop 6^g, said plate 6^a near its lower end having a stop 6^h, means for securing said plate 6^a to one of said bodies, said plate 6^a including a plate section 6^b extending in a plane at right angles to the plane containing the plate 6^a, said section 6^b forming one element of a hinge joint; the other hinge member comprising a second main plate 7^a secured to the other of said bodies and contacting said arc plate 6^a, said plate 7^a having a finger member 7^d to project over the plate 6^a at its curved edge and operate between the stops 6^g and 6^h of said plate 6^a, said second main plate 7^a having a plate section 7^b formed with the plate 7^a and held in a plane at right angles thereto, said plate section 7^b forming the second element of a hinge joint, and a hinge pin passing through said elements of said hinge joint substantially as shown and described.

2. A fixed and a movable body, means for hinging said movable body to said fixed

body, said means comprising a pair of members the first of said members consisting of a main arc plate 6^a held in one plane and having a second plate section 6^b held in a plane at right angles to that containing the arc plate 6^a, said second plate section 6^b having eye portions to form one element of a hinge joint, means for securing said arc plate to one of said bodies, said arc plate having a peripheral stop 6^g at one end and having a stop 6^h near the other end, a second main plate 7^a held in contact with the arc plate 6^a and secured to the other of said bodies, said second main plate 7^a having a projecting finger 7^d to embrace the curved edge of said arc plate 6^a and move between the stops thereof, said second main plate 7^a having a plate 7^b formed with said second main plate 7^a and held in a plane at right angles thereto, said plate 7^b having eyes to form a second element of a hinge joint, and a hinge pin passing through all of said eyes to hingedly connect said pair of members together.

FRANK T. LIPPINCOTT.
